UNITED STATES PATENT OFFICE.

JOHN M. ROHLFING, OF ST. LOUIS, MISSOURI, ASSIGNOR TO AMERICAN CAR AND
FOUNDRY COMPANY, OF ST. LOUIS, MISSOURI, A CORPORATION OF NEW JERSEY.

FOLDING STAKE-POCKET.

1,123,144.

Specification of Letters Patent. Patented Dec. 29, 1914.

Application filed September 26, 1914. Serial No. 863,659.

To all whom it may concern:

Be it known that I, JOHN M. ROHLFING, a citizen of the United States, residing at the city of St. Louis, State of Missouri, have 5 invented a certain new and useful Improvement in Folding Stake-Pockets, of which the following is a full, clear, and exact description, such as will enable others skilled in the art to which it appertains to make 10 and use the same, reference being had to the accompanying drawings, forming part of this specification.

My invention relates to stake pockets designed primarily for use on railway cars, 15 and is in the nature of an improvement on the devices illustrated in my copending application filed July 11, 1914, Serial Number 854,056.

The purpose of the present invention is 20 to provide a form of pocket in which the stake can be very rigidly held so that it will not wabble or lean to one side; to provide an improved form of bracket for supporting the loops, and otherwise generally to 25 improve the construction of the device.

In the accompanying drawings,—Figure 1 represents a front view of my improved stake pocket. Fig. 2 represents a side view. Fig. 3 represents a detail showing a modified form of loop.

Referring specifically to the illustrations, it will be understood that 1 represents the brackets which are formed with laterally extending ears 1^a which are pierced for the 35 passage of attaching devices. These ears are formed at the sides of the pockets 4 and 5, thereby decreasing the height of the brackets and placing the attaching members in the line of thrust of the stake supporting 40 members.

6 represents loop members having the laterally extending extremities 7 which are supported on the brackets 1 in either the supporting pockets 4 or the retaining pockets 5. The supporting pockets are formed with a vertical front face, which, when the bracket is attached to the car wall, is spaced apart therefrom a distance just sufficient to accommodate the extremity 7 when the loop 45 is swung to its horizontal or operative position. The width of the retaining pockets 5 is sufficient, however, to accommodate the extremities 7 when the loop is in its vertical or inoperative position.

55 It will be noted that the brackets are

provided with two sets of retaining and supporting pockets, which are spaced apart from each other at either side of the aperture 1^b which is designed to accommodate an attaching member. Consequently, the 60 loops 6 will be supported apart from each other vertically, and will afford a firm support for the stake, and hold it securely upright. The lower loop is shallower than the upper loop, so that it will tightly embrace 65 the tapered end of the stake, while the said end of the stake will readily pass through the upper loop.

The loops and brackets are provided with the marginal strengthening flanges 8 which 70 greatly strengthen the parts without materially increasing the weight. The outer sides of the supporting and retaining pockets are closed by walls 9 against which the ends of the extremities 7 are adapted to abut 75 so as to relieve the stake embracing portion of the loop member and the inner edge of the bracket, which is farther removed from the attaching members, of the stresses occasioned by side lash of the stake.

The form of loop illustrated in Fig. 3 is 80 designed to give increased stability to the stake. It will be noted that the front wall of this loop is considerably wider than the extremities 7, and that the side walls taper 85 from the front wall to the extremities 7. This gives very broad contact surfaces about the stake, affording an additionally firm support therefor.

I am aware that the device is capable of 90 modifications which depart from the form illustrated without departing from the scope of the invention, and hence it is not my intention to be limited to the specific form shown.

95 What I claim is:

1. A folding stake pocket, comprising 100 brackets formed with retaining and supporting pockets spaced apart vertically and laterally disposed attaching portions, and vertically swinging stake engaging loops adapted to cooperate with said pockets.

2. A collapsible stake pocket comprising 105 brackets having pockets spaced apart vertically and laterally directed attaching members, and vertically swinging loops adapted to engage in said pockets, which loops have portions adapted to engage the side and front portions of the stake.

3. In a folding stake pocket, a loop sup- 110

porting bracket formed with pockets having a front wall and a side wall forming an abutment and adapted to coöperate with a supporting surface to close the pocket at the rear.

4. In a collapsible stake pocket, a vertically swinging stake engaging member having laterally directed extremities by which it is supported, a front stake engaging wall of greater width than said ex-

tremities, and side stake engaging walls tapering from the front wall to the extremities.

In testimony whereof I hereunto affix my signature in the presence of two witnesses, this 22nd day of September, 1914.

JOHN M. ROHLFING.
